UNITED STATES PATENT OFFICE.

HARRY P. FAIRCHILD, OF NEW YORK, N. Y.

DESIGN FOR A MATCH-BOX.

SPECIFICATION forming part of Design No. 19,894, dated June 10, 1890.

Application filed May 15, 1890. Serial No. 351,976. Term of patent 3½ years.

To all whom it may concern:

Be it known that I, HARRY P. FAIRCHILD, a citizen of the United States, residing at New York, in the county of New York and State of New York, have invented a new Design for Match-Boxes, of which the following is a specification.

My invention consists of a design for match-boxes of that class designed to be carried in the pocket.

The accompanying print is a front or face view of a box embodying my design. In outline the box is made with slightly convex or rounded ends, and its sides are formed with a waved contour composed of two depressions and three expansions or projections, the larger of these being along the center of the sides and the smaller ones being near the ends on each side, as clearly shown by the accompanying print. The face or front is ornamented by a raised figure in the form of a circle, or nearly so, this figure on one side being in the form of border having its outer

I claim—

The design for a match-box, as herein described and shown.

In witness whereof I hereunto set my hand in the presence of two witnesses.

HARRY P. FAIRCHILD.
